UNITED STATES PATENT OFFICE.

JULIUS SCHMITT, OF MINNEAPOLIS, MINNESOTA.

STAY-BOLT.

1,052,282.

Specification of Letters Patent.

Patented Feb. 4, 1913.

Application filed March 20, 1912. Serial No. 685,105.

To all whom it may concern:

Be it known that I, JULIUS SCHMITT, of Minneapolis, in the county of Hennepin and State of Minnesota, have invented a certain new and useful Improvement in Stay-Bolts; and I do hereby declare the following to be a full and exact but concise description of my invention, which I believe is a decided improvement over stay-bolts because of its 5 simplicity in its construction and durability in its use.

My invention has for its object to provide an improved stay-bolt, and to this end, it consists of the novel devices and combinations of devices, hereinafter described and defined in the claims.

The invention is illustrated in the single view of the accompanying drawing.

Referring to the drawing, the single figure is a view partly in plan and partly in horizontal section, showing three of the improved stay-bolts applied to the inner and outer sheets of a fire box and each thereof showing a different step required in securing the same to the said sheets.

The numeral 1 indicates the outer sheet of the fire box, and the numeral 2 indicates the inner sheet thereof. These two sheets 1 and 2 are provided, respectively, with a plurality of relatively large and relatively small screw threaded openings 3 and 4. The openings of the two sheets 1 and 2 are axially alined one with the other.

The improved stay-bolt is indicated as an 25 entirety by the numeral 5. At its extreme outer ends, the stay-bolt 5 is provided with an angular portion 6 to which a wrench may be applied for screwing the stay-bolt 5 into engagement with the sheets 1 and 2. 40 Inward of this angular portion 6, the stay-bolt 5 is provided with a screw threaded portion 7 the screw threads of which are adapted to register with the screw threads of the openings 3. At its extreme inner 45 end, the stay-bolt 5 is circumferentially reduced at 8 to afford a stop shoulder 9 adapted to be forced into engagement with the inner face of the sheet 2 under the rotary movement of the stay-bolt 5 at the time the 50 same is applied to the sheets 1 and 2. The reduced portion 8 is provided with screw threads that are adapted to register with the screw threads of the opening 4 that is axially alined with the opening 3 into which 55 the screw threaded portion 7 of the stay-bolt is mounted. Inward of the stop shoul-

der 9, the stay-bolt 5 is provided with a screw threaded portion 10 of the same diameter as the screw threaded portion 7. The intermediate portion 11 of the stay-bolt 5 between its screw threaded portions 7 and 10 is reduced in diameter by tapering the same in reversed directions toward the axis of the stay-bolt 5.

The stay-bolt 5 at the left in the drawing shows the finished product. In applying the stay-bolt 5 to the sheets 1 and 2, the screw threaded portion 10 is first screwed completely through one of the openings 3. After this is done, the intermediate section 70 11 is free to be moved endwise completely through the opening 3. Next the screw threaded portion 7 is screwed into the opening 3 to an extent sufficient to bring the stop shoulder 9 into tight engagement with the sheet 2. During this same operation, the reduced portion 8 is screwed into the opening 4.

After the stay-bolt 5 is secured into position to the sheets 1 and 2, its outer or front 80 end portion is cut off, as shown by the intermediate stay-bolt 5. The cutting off of the front end of the stay-bolt 5 may be accomplished by any suitable tool, not shown, or it may be done in the customary manner of reducing or weakening the stay-bolt at the time the same is manufactured and at a point where it is desired to cut the same off to a sufficient extent to permit the front end of the stay-bolt 5 to be twisted off by a continued movement of the applied wrench after the stop shoulder 9 has been firmly seated against the sheet 2.

The next and final operation in securing the stay-bolt 5 to the sheets 1 and 2 is to upset the front and rear projecting ends thereof to form, respectively, rivet heads 7^a and 8^a. Obviously, the shoulder 9 and rivet head 8 securely hold the sheet 2 against the action of the heat and also prevent any leakage from the boiler into the fire box. It is also evident that by providing the portion 10 of the stay-bolt 5 with screw heads, the maximum width to the stop shoulder 9 is given. By reducing the diameter of the stay-bolts 5 at their intermediate portions, the danger of breakage due to the expansion and contraction thereof is largely overcome.

The above described device, while extremely simple and of comparatively small 110 cost to manufacture, is thought to be highly efficient for the purpose had in view.

What I claim is:—

1. A stay-bolt having screw threaded end portions adapted to be screwed into screw threaded openings in the inner and outer sheets of a fire box, and also having near its inner end a stop shoulder for engagement with the said inner sheet, the intermediate portion of said stay-bolt being tapered in reverse directions inward toward the axis of the stay-bolt, and the outer projecting ends of said stay-bolt being upset against the said two sheets to form rivet heads.
2. A stay-bolt having relatively large and relatively small screw threaded end portions adapted to be screwed respectively into screw threaded openings in the outer and inner sheets of a fire box, said stay-bolt inward of its relatively small screw threaded portion being increased in diameter to afford a stop shoulder adapted to engage with said inner sheet, said increased portion of said stay-bolt having screw threads of the same diameter as the said relatively large screw threaded end portion of said stay-bolt.
3. A stay-bolt having relatively large and relatively small screw threaded end portions adapted to be screwed respectively into screw threaded openings in the outer and inner sheets of a fire box, said stay-bolt inward of its relatively small screw threaded portion being increased in diameter to afford a stop shoulder adapted to engage with said inner sheet, said increased portion of said stay-bolt having screw threads of the same diameter as the said relatively large screw threaded end portion of said stay-bolt, the intermediate portion of said stay-bolt being tapered in reverse directions inward toward the axis of said stay-bolt.

JULIUS SCHMITT.
